UNITED STATES PATENT OFFICE.

MAX F. E. STADTMUELLER, OF POMEROY, IOWA.

BUTTER-WORKER.

SPECIFICATION forming part of Letters Patent No. 417,597, dated December 17, 1889.

Application filed June 17, 1889. Serial No. 314,647. (No model.)

To all whom it may concern:

Be it known that I, MAX F. E. STADTMUELLER, a resident of Pomeroy, in the county of Calhoun and State of Iowa, have invented 5 certain new and useful Improvements in Butter-Workers; and I do hereby declare that the following is a full, clear, and exact description of the invention, which will enable others skilled in the art to which it appertains to 10 make and use the same.

The invention relates to improvements in machines for working butter when taken from the churn to salt the same and remove the buttermilk therefrom; and it consists in the 15 construction and novel combination of parts hereinafter described, illustrated in the accompanying drawings, and pointed out in the claims.

Figure 1 of the drawings represents a perspective view of a butter-working machine embodying the invention, showing the dog or détent to hold the clutch open. Fig. 2 represents a central vertical longitudinal section thereof. Fig. 3 represents a rear end view of 25 the machine, showing the pulley, clutch, and adjacent parts, the clutch being partially in section to show the spline or feather on the shaft.

Referring to the drawings by letter, A designates the frame of the machine, of general 30 rectangular shape and provided with the upper side rails a a , which project rearward beyond the main portion of the frame and have bearings on said projecting ends for the operating-shaft, hereinafter described.

a' a' are the front legs of the main frame A, and a^2 a^2 the rear legs thereof. The front legs rise to the upper edges of the corresponding side rails a , while the rear legs rise a suitable 40 distance above said edges to form the standards a^3 a^3 .

B is the horizontal working-platform of the machine, above which platform the side rails a rise a suitable distance. The said platform is preferably longer than it is broad, and has at 45 its front and rear ends the strips b b' , respectively. The said strips are inclined downward and inward at angles of about forty-five degrees, and their upper edges are flush with those of the side strips a . The platform or table B thus forms the floor of a shallow receptacle X, in which the butter is worked and

from which the buttermilk can escape through the aperture b^2 in the rear strip b' .

b^3 is the upper front rail of the main frame 55 connecting the front legs a' thereof and lying against the outer side of the strip b .

Below the platform B a chamber C is formed by the side rails c , connecting the front and rear legs of the main frame just below the 60 rails a , and the bottom c' , preferably of sheet metal, secured to the lower edges of the rails c at its side edges, at its front edge to the upper edge of the lower front rail c^2 of the main frame, and at its rear edge to the lower edge 65 of the lower rear rail c^3 , which closes the rear of the chamber C. The said chamber serves to contain ice in summer to keep the butter cool while being worked, its front end being open and the water from the ice escaping 70 through the opening c^4 in the rear rail c^3 .

D is a shaft with its ends journaled in the bearings on the rearward extensions of the side rails a , and having on its ends outside of 75 said bearings the similar crank-arms d .

E is a frame composed of two side bars e e , having their rear ends pivoted to the tops of the corresponding standards a^3 and the transverse bars e' e' , to which the rear end of the longitudinal handle e^2 is secured. 80

F F are swinging or vibratory levers having their upper ends pivoted to the front ends of the bars e of the frame E, and thence extending downward, with their lower parts lying against the outer surfaces of the sides 85 of the main frame.

G is a roller fitting transversely between the side rails a , its journals having bearings in the vibratory levers at suitable points. The said journals are provided with suitable washers and transfixing-pins outside of their bearings to hold them in place, and the levers F, by hugging the side rails a and c , act somewhat as guides for the roller G. 90

H H are pitmen that connect the ends of 95 the crank-arms d with the levers F at suitable points above the roller-bearings. By means of these pitmen the rotation of the crank-arms with the shaft D will swing or vibrate the levers F, and will consequently move the roller alternately frontward and rearward over the working-platform.

h is a bar pivoted at its lower end on the front rail b^3 . The said bar stands normally

vertical and is sufficiently high to catch upon its top the handle e^2 , thus providing a support for the free end of the handle, and also causing the levers F to lift the roller at the forward end of the stroke, so that the same cannot crush the butter against the ends of the strips b and thereby break the oil-globules. By the said strips being inclined at angles of forty-five degrees the roller in rising near the ends of the working-platform will be prevented from squeezing the butter against their upper edges. By means of the handle e^2 the roller can be raised and depressed, and the pressure on the butter thereby regulated. h' is an arm or bar secured to one of the standards a^3 and inclining upward and rearward therefrom. The frame E and roller can be lifted and supported upon the bar h' when it is necessary to clean the platform or for other purposes.

I is a pulley turning loosely on the shaft D, and with its hub on one side constituting one section i of the shouldered clutch J, the opposite section j of which is splined on the said shaft, so that it can move thereon only longitudinally. The pulley is prevented from moving longitudinally by pins which transfix the shaft on each side of it, or by other suitable means. The section j is provided with the usual circumferential groove j' for the fork k of the longitudinal operating-rod K, that has bearings in the lower part of the main frame.

The rod K has a rear arm k' , that rises vertically to its fork, and a front arm k^2 , that stands horizontally outward, so that by pressing the said front arm downward with his foot the operator turns the rear arm outward and disengages the sections of the clutch.

When the front arm is thus depressed, the detent L, which is pivoted at its lower end upon the side of a front leg of the machine, falls slightly forward, and the notch l in the edge of said detent catches over the front arm and retains the clutch open. The operator can also with his foot move said front arm outward from the notch l and release it from the detent L. The section j of the clutch is then immediately closed on the section i by the coiled spring M, that surrounds the shaft D between the outer ends of the section j and a pin transfixing the shaft.

The rod K is preferably made from pipe or tubular for the sake of lightness, and the pulley I may be run by a belt from any proper motor. (Not shown in the drawings.)

Having thus fully described my invention, what I claim as new, and desire to secure by Letters Patent, is—

1. In a butter-working machine, the combination, with the front uprights, of the rear uprights extending higher than the front uprights, the side, end, and bottom pieces forming a shallow receptacle, the forwardly-extending arms pivoted to said rear uprights, transverse pieces connecting said forwardly-

extending arms, downwardly-extending arms having their upper ends pivoted to said forwardly-extending arms, the transverse shaft journaled in the lower ends of said vertical arms, said shaft carrying a suitable roller, and means, substantially as described, for actuating said vertically-extending arms, substantially as set forth. 70

2. The combination, with the receptacle of a butter-working machine, of the rear standards or uprights extending upwardly a greater distance than the front uprights, the upper movable frame consisting of the forwardly-extending arms pivoted to the rear uprights, the connecting transverse bars, the downwardly-extending pivoted arms, and the arm secured to one of the side pieces of the frame and slanting rearwardly, adapted to support the upper frame when the same is thrown back for cleaning, substantially as set forth. 75

3. In a butter-working machine, the combination of the front uprights, the rear uprights extending higher than the front uprights, the end and bottom pieces, the said pieces extending beyond the rear end piece, the upper movable frame consisting of the forwardly-extending arms pivoted to the rear uprights, the transverse connecting-pieces, and the downwardly-extending arms pivoted to said forwardly-extending arms, the transverse shaft journaled in the lower end of the vertical arms, said shaft carrying a suitable roller, a rear transverse shaft mounted in bearings in the extended rear portions of the said pieces, a pulley-wheel mounted upon said shaft, cranks upon opposite ends thereof, and pitmen connecting the cranks and downwardly-extending arms, substantially as set forth. 90

4. In a butter-working machine, the combination, with the working-platform having the inclined strips at its ends, of the frame pivoted to the standards at the rear end of the platform, the swinging levers pivoted to said frame, the roller journaled in and between said levers, the longitudinal handle secured to said pivoted frame, and the vertical rod pivoted to the front of the main frame of the machine and preventing the entire descent of said handle when the roller is about to reach either end of the platform, substantially as specified. 100

5. In a butter-worker, the combination of the uprights or standards, the lower cross-strips, the rear one of which being higher than the front strips and provided with a perforation, the lower side rails, the bottom piece having one end secured beneath the rear cross-strip and the other secured to the upper edge of the front cross-strip, the upper side pieces secured to the standards, the upper cross-pieces, the inner inclined pieces resting against said upper cross-pieces, the rear one thereof being provided with a perforation and the space between the two receptacles forming a lower open-ended cool- 110

ing-chamber, the roller, and mechanism, substantially as described, whereby said roller is operated, substantially as set forth.

6. In a butter-working machine, the combination, with the frame provided with a horizontal working-platform, of a shaft journaled in the rear portion of said frame, a loose belt-pulley mounted upon said shaft, having its hub on one side constituting one section of clutch, the spring-actuated outer section of clutch, splined upon said shaft, said outer section provided with a circumferential groove, the longitudinally-operating rod mounted in bearings in the lower part 15 of the frame and provided with a rear vertically-extending arm terminating in a fork which engages the circumferential groove, and having its front end terminating in a right-angled extension, the detent for engaging said section, the forwardly-extending arms pivoted to the rear standards of the frame, the cross-bars connecting said arms, the downwardly-extending arms articulating

with the ends of said inwardly-extending arms, a roller journaled in the lower ends of 25 said downwardly-extending pivoted arms, cranks secured upon opposite ends of the rear pulley-shaft, and pitmen connecting said cranks and downwardly-extending arms, substantially as set forth.

7. The combination, with the working-platform, of the driving-shaft and pulley, the crank-arms on the ends of said shaft, the frame pivoted to standards at the rear of the main frame, the swinging levers, the roller 35 journaled to and between said levers, and the pitmen connecting said levers and crank-arms, substantially as specified.

In testimony that I claim the foregoing as my own I have hereunto affixed my signature 40 in presence of two witnesses.

MAX F. E. STADTMUELLER.
